[57] CLAIM

The ornamental design for an electronic calculator, as shown.

DESCRIPTION

FIG. 1 is a perspective view of the electronic calculator showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and

FIG. 7 is a left side elevational view thereof.
